WEFT REPLENISHING MECHANISM
FOR LOOMS

Osias J. Le Blanc, North Oxford, and Robert S. Schedin, Worcester, Mass., assignors to Crompton & Knowles Loom Works, Worcester, Mass., a corporation of Massachusetts

Application September 18, 1948, Serial No. 49,962

7 Claims. (Cl. 139—245)

1

This invention relates to improvements in weft replenishing looms, more particularly of the multicolor type, and it is the general object of the invention to provide means actuated by some part of the weft replenishing mechanism to prevent or resist rotation of reserve bobbins in the replenishing mechanism.

Many multicolor weft replenishing looms are provided with a magazine having vertical stacks of reserve bobbins which move by gravity toward transfer position. The several stacks are arranged between guideways which necessarily maintain a loose fit with the bobbins to permit the latter to move down by gravity and because of this loose fit the bobbins rotate on their axes due to vibration incident to loom operation. This rotation of the bobbins is likely to cause either undue slackness of their weft ends, or tightening of the weft ends to such an extent that thread breakage may result.

In the past various means have been provided for the purpose of resisting bobbin rotation in weft replenishing mechanisms or magazines of the multicolor type, and some of these have included resilient strips of metal or the like located in the bobbin guideways for engagement with the bobbins. So far as is known, however, these devices have acted on the bobbins merely by their resilience, and if the magazine should be subject to vibration in the direction of the length of the bobbins the latter are likely to overcome the resilience of the anti-rolling means. Such resilient means have been under control of some part of the magazine, but this part has acted merely to move the resilient devices to non-bobbin restraining position at the time of bobbin transfer and have not been utilized to exert a positive force on the resilient devices to hold them against the bobbins.

It is an important object of the present invention to provide a bobbin magazine of the type already referred to with a resilient bobbin engaging member which is normally forced into bobbin engaging position by some part of the magazine during non-replenishing conditions, said part being preferably a vertically slidable bobbin releaser. When a replenishing operation occurs this part moves from its normal to a temporary abnormal position to release the bobbin engaging member, whereupon the latter due to its resilience moves away from the bobbins to free the latter so they may fall by gravity.

The aforesaid bobbin releaser is provided at its upper end with a pivoted dog which during downward movement of the releaser after a previous raising thereof swings pivotally with respect to the releaser. It is a further object of the invention to operate the resilient bobbin restraining member which engages the bobbins by these dogs as the latter return to their normal

2

position incident to downward movement of their respective releasers.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation of parts of a weft replenishing loom showing the reserve bobbin magazine with the invention applied thereto, and showing the lay in cross section,

Fig. 2 is an enlarged vertical section on line 2—2, Fig. 1,

Fig. 3 is an enlarged detailed horizontal section on line 3—3, Fig. 2, showing one bobbin releaser and associated parts,

Fig. 4 is a vertical section on line 4—4, Fig. 3, showing one of the vertical slides and the dog therefor in two different positions, and

Fig. 5 is a perspective view of one of the bobbin engaging members.

Referring particularly to Figs. 1 and 2, the loom frame 10 supports a magazine designated generally at M, the magazine being of the usual multicolor type and having in this particular instance four stacks of reserve bobbins designated generally at B1, B2, B3 and B4 arranged from right to left as viewed in Fig. 1. These stacks are arranged between inner and outer magazine plates 11 and 12 shown at the left and right, respectively, of Fig. 2. The inner plate 11 is provided with flanges 13 which define guideways G for the butts 14 of the reserve bobbins, and in similar manner the outer plate 12 is provided with flanges 15 defining guideways for the tips 16 of the reserve bobbins.

At the bottom of each stack there is located a rockable bobbin delivering cradle one of which is shown at 20 in Fig. 2. These cradles are controlled by upright bobbin releaser slides 21, 22, 23 and 24 for the stacks B1—B4, respectively. These releaser slides are normally in down position and are provided with upper and lower lugs 25 and 26, respectively, which cooperate with a so-called color slide 27 having operating fingers 28. When four stacks of bobbins are used as set forth herein, there will be two fingers 28, one of which is partly broken away in Fig. 2. The usual guides 29 allow the releaser slides to move vertically but prevent them from moving laterally away from the inner plate 11. The color slide has a longitudinal motion transverse of the vertical slides and also has a rocking motion for the purpose of raising and lowering any releaser slide registered with it.

Whenever a weft replenishing operation is called the color slide 27 will rock in a counter-clockwise direction as viewed in Fig. 2, and the fingers 28 will rise to engage the top lug 25 of

the vertical slide registered with one or the other of them to raise the corresponding slide. At some later time the color slide 27 is given a clockwise rocking movement the effect of which is to engage the bottom lug 26 of the previously raised vertical slide to lower the latter. As the vertical slide rises it rocks its cradle so that the latter receives the lowest bobbin in the associated stack, and as the vertical slide descends the cradle is returned to its normal position and at the same time discharges the previously received bobbin so that the latter can move to a transfer position indicated at B, Figs. 1 and 2, under a transerrer arm 35.

Each vertical slide has a dog 30 pivoted at 31 to the upper end thereof. A compression spring 32 between the head 33 of the vertical releaser slide and the arm 34 of the dog tends to move the latter in a clockwise direction as viewed in Fig. 4. When the vertical slide is down, however, the arm 34 engages the web 35 of end plate 11 and the dog will be held in the dotted line position shown in Fig. 4. As the vertical releaser slide rises and arm 34 moves away from the web 35 the spring 32 rocks the dog to the full line position shown in Fig. 4 with arm 34 inclined downwardly. Upon subsequent downward movement of the vertical slide the dog engages web 35 and returns to normal position with arm 34 horizontal.

The matter thus far described is well understood and may be of usual construction and operate in the usual manner.

In carrying the present invention into effect each bobbin stack or guideway G is provided with a bobbin butt engaging member which normally resists movement of the associated bobbins. In the present instance there will be four of these devices, but since they are all alike the description herein will be limited to one of them, namely, the member associated with the front bobbin stack B1.

The resilient bobbin engaging friction member, designated generally at 40, and shown more specifically in Fig. 5, has a long flat body 41 made of some suitable material, such as sheet spring steel, and is proportioned to fit between the flanges 13 of guideway G corresponding to the bobbins of stack B1. The vertically extending body 41 of member 40 lies between the butts 14 of the associated bobbins and the web 35. The upper part of the bobbin restraining member 40 lies closely against one side of web 35 and is bent over laterally as at 42 so that it will fit over the top of the web 35. The end of the member is then bent down as at 43 parallel to body 41 to resiliently engage the opposite side of web 35, see Fig. 2. In order that the bobbin restraining member may be held against accidental upward motion there is struck from it a small finger 44 which fits under that part of the web 35 which is gripped by the body 41 and end 43. The straight downbent end 43 together with the body 41 cooperate with the web 35 to hold the lower part of the member 40 against web 35 and cause the body 41 normally to tend to move away from the bobbin butts.

Struck from the member 40 is an integral tongue 45 which is inclined downwardly and away from the bobbins, and is positioned for engagement with the arm 34 of the dog 30. When the releaser slide 21 is down as shown in Fig. 2, and in dotted lines in Fig. 4, the horizontal arm 34 will bear against the tongue 45 and push the

member 40 to the dotted line position shown in Fig. 4 against the butts of the bobbins in the corresponding stack. When held in this position the member 40 effectively prevents rotation or objectionable vibration of the bobbins, and resists downward motion of the bobbins by gravity. It should be noted that the member 40 is held in this position positively, the arm 34 extending horizontally to the right from its pivot 31 to exert a lateral force on the member 40 transmitted through the tongue 45. This is a normal condition and persists until a replenishing operation occurs involving bobbins from stack B1. At that time the vertical slide 21 will rise and the spring 32 will rock the dog 30 as already described, thereby inclining the arm 34 of the dog downwardly to the full line position shown in Fig. 4 and moving it laterally away from the member 40 at the same time the dog moves upwardly away from the tongue 45. The member 40 is therefore free to move by its resilience to the full line position shown in Fig. 4 away from the bobbin butts 14, and the bobbins are thus released so that they can fall freely to permit the lowermost bobbin thereof to move into the corresponding cradle 20. When the previously raised vertical slide is again depressed by action of the color slide 27 the arm 34 of the dog rocks from the inclined full line position 30 to the horizontal dotted line position of Fig. 4 and again exerts force through tongue 45 to move the member 40 against the bobbin butts 14.

From the foregoing it will be seen that the invention provides a simple means for preventing objectionable vibration or rotation of reserve bobbins as they await transfer in a bobbin magazine. The mechanism includes a member 40 which is positively acted upon and forced against the bobbins by a magazine part, such as a bobbin releaser slide, when the latter is in normal position. When a replenishing operation occurs the vertical releaser slide moves away from the restraining member 40 and the latter because of its resilience then moves away from the bobbin butts to release the bobbins so they may fall by gravity. It will also be seen that the bobbin engaging member is controlled by the pivoted dog on the vertical releaser slide, and that the force which holds the member 40 in normal bobbin restraining position is substantially perpendicular to the direction in which the slide reciprocates vertically and therefore does not subject the slide to any unbalanced force which might otherwise disturb its normal position. Furthermore, the movement of the member 40 against the bobbin butts is effected by two factors one of which is the downward motion of the dog as it engages the tongue 45 and the other of which is the angular motion of the dog which moves the arm 34 thereof from an inclined to a horizontal position.

Having thus described the invention it will be seen that changes and modifications of the foregoing specific disclosure may be made without departing from the spirit and scope of the invention.

What is claimed as new is:

1. In a weft replenishing mechanism having a stack of bobbins which move downwardly by gravity toward transfer position, a resilient member mounted on the mechanism tending due to the resilience thereof to move away from the bobbins, and bobbin releaser means movable from one position thereof to another position thereof incident to a weft replenishing operation of the

mechanism, the releaser means in said one position thereof engaging and forcing the member against the bobbins to resist movement of the latter, the releaser means in the other position thereof being out of engagement with the member, whereupon the latter moves away from the bobbins to enable the latter to fall toward transfer position without interference by the member.

2. In a weft replenishing mechanism having a stack of bobbins which move downwardly by gravity toward transfer position, a bobbin releaser movable upwardly from the normal position thereof to an abnormal position incident to a weft replenishing operation of the mechanism, a dog pivoted on said releaser and having an arm which is substantially horizontal when the releaser is in the normal position thereof, the arm assuming a downwardly inclined position when the releaser is in the abnormal position thereof, and a vertically extending resilient friction member for the bobbins supported on the mechanism and forced against the bobbins by said arm to resist movement of the bobbins when the releaser is in the normal position thereof, said dog when moving to the inclined position thereof incident to upward movement of the releaser to the abnormal position of the latter moving away from the member and the latter due to the resilience thereof moving away from the bobbins.

3. In a weft replenishing mechanism having a stack of bobbins which move downwardly by gravity toward transfer position, a resilient friction member extending vertically and supported by the mechanism and tending due to the resilience thereof to move away from the bobbins, a bobbin releaser normally in down position but raised to an abnormal position incident to a weft replenishing operation of the mechanism, a dog pivoted on the releaser having an arm normally engaging part of the replenishing mechanism and being disposed substantially horizontally when the releaser is in the normal down position thereof and engaging the member to force the latter against the bobbins to resist movement of the latter, and means effective as the releaser moves to the abnormal position thereof and the arm moves away from said part of the replenishing mechanism to move said arm downwardly and in a direction away from said member.

4. In a weft replenishing mechanism having a stack of bobbins which move downwardly by gravity toward transfer position, a bobbin releaser slideable vertically on the mechanism from a normal down position to an abnormal up position incident to a weft replenishing operation of the mechanism, a dog pivoted to the releaser and having an arm which is in horizontal position when the releaser is down and is in a downwardly inclined position when the releaser is in abnormal position, and a resilient friction member extending vertically and supported on the mechanism for engagement with the bobbins and having a tongue thereon for engagement with the arm, said member due to the resilience thereof tending to move away from the bobbins, the arm normally engaging the tongue and forcing the member against the bobbins to resist movement of the latter when the releaser is in the normal down position thereof, and the dog rising to a position out of engagement with the tongue when the re-

leaser rises to the abnormal position thereof, said arm when moving to the inclined position thereof moving away from the member, whereupon the latter due to resilience thereof moves away from the bobbins.

5. A weft replenishing mechanism having a stack of bobbins which move downwardly by gravity toward transfer position, a vertically extending resilient friction member for engagement with the bobbins tending due to the resilience thereof to move away from the bobbins, a tongue on said member inclined downwardly and in a direction away from said bobbins, an upwardly slideable releaser on the mechanism on that side of the member opposite the bobbins, a dog pivoted to said releaser, the releaser being normally down and part of the dog normally engaging the tongue to force the member against the bobbins to resist movement of the latter, the releaser when rising lifting the dog to a point above said tongue out of engagement with the latter, and means effective when the releaser moves upwardly to move the dog pivotally so that said part thereof moves away from said member.
- 10 6. In a weft replenishing mechanism having a stack of bobbins which move downwardly by gravity toward transfer position, an end plate forming part of the replenishing mechanism, a resilient bobbin engaging member extending vertically along the bobbins and having the upper end thereof bent over and downwardly along a part of said end plate, a finger struck from said member engaging the under side of said part of the end plate, said upper end and finger of the member in cooperation with said part of the end plate tending to hold the member away from said bobbins, means movable on the replenishing mechanism effective in one position thereof to force said member against the bobbins to resist movement thereof, said means in another position thereof being out of engagement with the member and enabling the latter due to the resilience thereof to move away from said bobbins.

7. A member to resist movement of reserve bobbins in a weft replenishing mechanism having a bobbin releaser slideable on an end plate formed with a web forming part of a guideway for the butts of the bobbins, said member comprising a single strip of flat resilient material having an elongated straight body to extend along said guideway, one end of said body being bent laterally from the body in a given direction and is then further bent to extend parallel to but spaced from the body to fit over part of said web, a finger integral with the body extending from the latter in said given direction to lie under said part of the web, and said body having a tongue to engage said releaser integral with said body extending therefrom in said given direction.
